(57) **CLAIM**

The ornamental design for a wearable player, as shown and described.

DESCRIPTION

FIG. 1 is a front elevational view of a wearable player showing our new design;

FIG. 2 is a rear elevational view thereof;

FIG. 3 is a top plan view thereof;

FIG. 4 is a cross sectional view thereof cut along the line 4-4 of FIG. 3;

FIG. 5 is an enlarged cross sectional view thereof cut along the lines 5-5 and 5'-5' of FIG. 3;

FIG. 6 is an enlarged cross sectional view thereof cut along the lines 6-6 and 6'-6' of FIG. 3;

FIG. 7 is an enlarged cross sectional view thereof cut along the lines 7-7 and 7'-7' of FIG. 3 showing the left side block thereof;

FIG. 8 is an enlarged cross sectional view thereof cut along the lines 8-8 and 8'-8' of FIG. 3 showing the right side block thereof; and,

FIG. 9 is an enlarged cross sectional view thereof cut along the lines 9-9 of FIG. 1 and the line 9'-9' of FIG. 3.

Portions in broken lines are for illustrative purposes only and form no part of the claimed design. Dot-dash broken lines define the boundaries of, but not included in, the claimed design.
